UNITED STATES PATENT OFFICE.

ALVAH C. ROEBUCK, OF CHICAGO, ILLINOIS, ASSIGNOR TO WOODSTOCK TYPEWRITER COMPANY, OF WOODSTOCK, ILLINOIS, A CORPORATION OF ILLINOIS.

UNIVERSAL BAR.

1,276,118.

Specification of Letters Patent. Patented Aug. 20, 1918.

Application filed April 25, 1914, Serial No. 834,554. Renewed January 22, 1918. Serial No. 213,267.

To all whom it may concern:

Be it known that I, ALVAH C. ROEBUCK, a citizen of the United States, residing at Chicago, in the county of Cook and State 5 of Illinois, have invented certain new and useful Improvements in Universal Bars, of which the following is a specification.

This invention relates to typewriters and more particularly to that portion of the 10 escapement mechanism of a typewriter commonly known as the universal bar.

The principal object of the invention is to provide a universal bar which is engaged by the type bars of the printing mechanism 15 behind the type bar segment in which the type bars are pivotally mounted, the universal bar proper being of such construction and formation that erasures, dirt, grit and the like will fall upon or be deflected by the 20 universal bar and are prevented from being thrown into the bearings or slots of the type bars through the quick movement of the universal bar after being struck by the heel of any of the type bars.

Other and further objects will be herein- 25 after set forth, the invention consisting in the features of novelty in the construction, combination and arrangement of the several parts generally shown in the accompanying 30 drawings and described in the specification, but more particularly pointed out in the appended claims.

In the drawings, Figure 1 is a bottom view of escapement mechanism comprising 35 a universal bar constructed in accordance with the principles of my invention.

Fig. 2 is a side elevation of the same.

Fig. 3 is a rear view.

Fig. 4 is a perspective view of the universal bar proper and its frame.

Fig. 5 is a detail view in cross section of the preferred form of universal bar; and

Fig. 6 is a detail sectional view of another form of universal bar proper.

This embodiment of my invention comprises an escapement mechanism consisting of a number of parts which are adapted to be mounted on the under side of a top plate 8 of a typewriter machine. Extending 50 downwardly from the rear part of this top plate are lugs 9 in which a rocker 10 is

mounted. Secured to another part of the frame 8 is a type bar segment 11 with slots 12 in which type bars 13 are pivotally mounted on a pivot wire 14. The rear of 55 the type bar segment 11 is formed with an arcuate groove 15 which passes through the slots 12, thereby providing a construction in which a heel 16 of the type bars 13 is permitted to enter the groove upon the actuation of the type bars to engage and move the universal bar, as hereinafter set forth.

A universal bar frame 17, preferably constructed of sheet metal, is formed with depending ears 18 at the rear end which are 60 pivotally connected to the lower extremities of the rocker 10. At the forward end of the frame 17 are arms 19 to support the universal bar 20. This universal bar 20 is also arcuate in form and is adapted to enter 70 the groove 15 in the rear face of the type bar segment 11 so that when the type bars 13 are actuated it will be engaged and moved rearwardly by the heel 16 of each of the type bars. This rearward movement is op- 75 posed by a spring 21 disposed between the frame 8 and the rear of the rocker 10 which operates to return the universal bar 20 to its groove 15 as soon as the type bars 13 are withdrawn from the printing position. At 80 the forward end of the frame 17 is an adjustable spindle 22, the end of which is adapted to enter a perforation in the type bar segment 11 to accurately guide the front end of the universal bar frame 17. Escape- 85 ment mechanism, designated generally by the reference numeral 24, is connected to the rear end of the frame 17 and is operated in accordance with the movement of the frame 17.

The universal bar proper preferably consists of a piece of sheet metal bent in the form of an arc with its front edge 25 turned upwardly, as shown clearly in Fig. 5. This turned-up portion is adapted to be seated in the groove 15 when the universal bar is at rest, and the bar is provided with perforations 26 at its lowermost or central portion through which dirt, etc., may pass. The universal bar is inclined downwardly and 95 away from the up-turned edge and away 100 from the type bar segment 11 so that any

erasures or dirt falling upon the inclined surface will be deflected outwardly from the universal bar and will not fall in the slots 12 of the type bar segment. It is also 5 to be noted that the quick rearward movement of the universal bar, caused by the engagement of the type bars therewith, tends to cause any particles lodged on the universal bar to travel forwardly so that unless the universal bar is inclined, or is provided with the ridge 25 at its forward edge, 10 the erasures and dirt may be thrown into the type bar slots. The holes 26 at the lower-most portion of the universal bar may be used as an auxiliary to prevent the accumulation 15 of erasures or dirt at this place since it is evident that if the dirt piles up at this point the quick movement of the universal bar may throw it over the ridge 25. If desired, the ridge 25 may be omitted, as shown in Fig. 6, but the universal bar is inclined for the purpose of deflecting dirt 20 from the type bar slots and for preventing the dirt from being thrown into the slots by the quick movement of the universal bar.

This construction is particularly well adapted for assembling the parts with the greatest facility; the top plate 8 is inverted in assembling, as shown in Fig. 1, and the 30 rocker 10, frame 17 and escapement mechanism are readily placed in position. When the top plate is connected to the remainder of the typewriter machine the segment 11 is secured to the proper portion of the plate 35 8, the universal bar is seated in the groove 15 at the rear of the segment and the universal bar frame 17 is positioned at its forward end by means of the spindle 22, after which the tension of the spring 21 may be 40 adjusted, as desired. This convenience in assembling is one of the very important features of the construction of a typewriter inasmuch as it is made up of a great many parts and the expense and convenience of 45 assembling it is an important item in its construction.

What I claim is:

1. In a typewriter, a type bar segment, and a horizontally reciprocable universal 50 bar moving toward and from the type bar segment with its upper face inclined downwardly away from the segment to deflect falling dirt therefrom and to discharge dirt from the bar by its movement in a direction 55 away from the segment.
2. In a typewriter, a universal bar consisting of a strip of material arcuate in form with the ends higher than the center and horizontally reciprocable, the central portion 60 having a downwardly inclined upper face to divert falling dirt and to discharge dirt therefrom in a predetermined direction.
3. In a typewriter, the combination with 65 a slotted type bar segment having a groove

in the rear face across the slots, and a universal bar adapted to be seated in the groove over the slots with an inclined upper face to deflect and by its movement to discharge dirt therefrom in a direction away from the slots. 70

4. In a typewriter, a universal bar consisting of a strip of material turned up at its forward edge to form a dirt protecting ledge.

5. In a typewriter, a universal bar consisting of a strip of material turned up at its forward edge to form a dirt protecting ledge and inclined downwardly from said ledge to form a dirt deflecting surface. 75

6. In a typewriter, the combination with 80 a slotted type bar segment, of a groove extending across the slots in the rear face of the segment, and a universal bar movable toward and from the segment with a ledge at its contacting edge and a deflecting surface inclined downwardly therefrom adapted 85 to be seated in the groove.

7. In a typewriter, the combination with 90 a type bar segment in which type bars are pivoted and having a groove in the rear face thereof above the type bar pivots, of a reciprocal universal bar having a forward ledge and upper deflecting surface adapted to be seated in the groove.

8. In a typewriter, the combination with 95 a slotted type bar segment in which type bars are pivoted and having a groove in the rear face thereof above the type bar pivots, of a universal bar formed with a deflecting surface and with an up-turned edge adapted 100 to be seated in the groove and movable to and from the segment.

9. In a typewriter, a universal bar consisting of a piece of material with an inclined upper face to form a deflecting surface and with perforations therethrough to prevent the accumulation of dirt thereon. 105

10. In a typewriter, a universal bar arcuate in form with an inclined dirt deflecting surface and with perforations through the 110 bar to prevent the accumulation of dirt at any place thereon.

11. In a typewriter, the combination of a slotted type bar segment, with type bars pivoted therein and a groove in the rear face 115 thereof extending through the type bar slots above the type bar pivots, of a reciprocal universal bar formed of a piece of material with an upper deflecting surface and an up-turned edge adapted to be seated in the 120 groove, and with perforations through the bar to prevent the accumulation of dirt thereon.

12. In a typewriter, the combination with 125 a slotted type bar segment, type bars pivotally mounted in the slots and formed with an engaging heel, of a universal bar with an upturned front flange adapted to be en-

gaged by the heel for moving it when the type bars are actuated, a reciprocable frame, and means to support the frame at its forward end in fixed relation with respect to 5 the type bar segment.

13. In a typewriter, the combination with a top plate, of a slotted type bar segment secured thereto, type bars pivotally mounted in the segment, a universal bar disposed 10 above the pivots of the type bars, a universal bar frame attached to the universal bar, means in connection with the frame at its rear end to mount it pivotally on the plate, and a spindle at its forward end inserted 15 through a perforation in the segment to support the frame with respect to the segment.

14. In a typewriter, the combination with a top plate, of a slotted type bar segment secured thereto and having a perforation in 20 the rear face, a universal bar adapted to engage the segment, type bars mounted in the slots and adapted to engage the universal bar, a rocker pivotally mounted at the rear of the plate, a universal bar frame pivotally 25 connected to the rocker and to the universal bar, and an adjustable spindle mounted on the front end of the frame and adapted to be inserted in the perforation in the segment to position the front end of the frame.

30 15. In a typewriter, the combination with a top plate, of a slotted type bar segment formed with a perforation and a groove in the rear face extending through the slots, a universal bar having a perforated deflecting 35 surface and a ledge at the forward and upper edge adapted to be seated in the groove, type bars pivotally mounted in the slots of the segment below the universal bar and formed with a heel to engage it, a rocker 40 pivotally mounted in the rear of the plate, a frame pivotally connected at one end to the rocker and at the other end to the universal bar, a spindle mounted on the front end of the universal bar frame 45 adapted to be seated in the perforation of the segment, and a spring between the rocker and the plate tending to press the rocker downwardly and the universal bar into the slot of the segment.

50 16. In a typewriter, the combination with a type bar segment, of type bars pivoted in the segment, a universal bar adapted to be engaged by the type bars, a reciprocable frame for the universal bar, a hinged support 55 for mounting the frame at the rear end thereof for free reciprocal movement, and a sliding connection between the frame and the segment at the forward end of the frame for supporting it for free reciprocation.

60 17. In a universal bar structure for typewriters, the combination with a top frame plate, of a type bar segment connected thereto, a rocker pivotally mounted in and depending from the plate, a universal bar

frame pivotally connected to the rocker at a 65 point below its pivot, and a guiding connection between the universal bar frame and the segment for guiding the universal bar frame in its reciprocating movement.

18. In a typewriter universal bar construction, the combination with a top supporting plate, of a type bar segment connected thereto, a rocker pivotally connected to the plate at the under side thereof, a universal bar frame pivotally connected at its 75 rear end to the rocker, a guide connection between the frame and the segment, and a spring disposed between the under side of the plate and the rocker, tending to press the frame forwardly in the direction of the 80 segment.

19. In a typewriter universal bar construction, the combination with a top supporting plate, of a type bar segment connected thereto, a rocker pivotally connected 85 to the plate at the under side thereof, a universal bar frame pivotally connected at its rear end to the rocker, a guide connection between the frame and the segment, a stop mounted on the rocker for limiting its 90 rearward movement, and a spring tending to press the rocker downwardly and the frame forwardly.

20. In a typewriter universal bar construction, the combination with a top supporting plate, of a type bar segment connected thereto, a rocker pivotally connected to the plate at the under side thereof, a universal bar frame pivotally connected at its rear end to the rocker, a guide connection 95 between the frame and the segment, a universal bar connected to the frame and disposed adjacent the segment, type bars pivoted in the segment adapted to engage the universal bar for moving it and the frame 100 rearwardly, a spring disposed between the rocker and the plate for opposing the rearward movement of the frame, and an adjustable stop mounted on the rocker for limiting the rearward movement of the frame and 110 the upward movement of the rocker.

21. In a universal bar structure for typewriters, the combination with a top plate having depending lugs spaced apart, of a rocker pivotally mounted in the lugs, extending rearwardly thence downwardly from the pivot point with extremities curved forwardly, a type bar segment secured to the plate, a universal bar frame pivotally connected at its rear end to the extremities 115 of the rocker, the pivot point lying below the pivot of the rocker, an adjustable guiding connection between the frame at its forward end and the segment, a universal bar supported by the frame adjacent the segment, type bars mounted in the segment adapted to engage the universal bar for moving it rearwardly, an adjustable stop 125

at the rear of the rocker for limiting the upward movement of the rocker with respect to the supporting plate, and a spring disposed between the rocker and the supporting plate, tending to press the rocker downwardly and the universal bar frame forwardly.

In testimony whereof I have signed my
